UNITED STATES PATENT OFFICE

WILLIAM H. WHITFORD, OF TULSA, OKLAHOMA

PENCIL SHARPENER

Application filed January 18, 1932. Serial No. 587,331.

This invention relates to pencil sharpeners, and its general object is to provide a sharpener primarily designed for mechanical pencils, the sharpener including a housing detachable from one end of the body of the pencil for the purpose of being received by the writing end thereof to sharpen the lead refill projecting from said end, with the result the sharpener at all times is carried by the pencil and can be used to provide a point on the lead in an easy and expeditious manner.

Another object of the invention is to provide a sharpener of the character set forth, that is extremely efficient in operation and service.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view of a mechanical pencil constructed to accommodate my sharpener and illustrates the latter associated therewith.

Figure 2 is a longitudinal sectional view taken through the housing of my sharpener attached to the eraser end of the body of the pencil with the sharpener parts in elevation.

Figure 3 is an enlarged elevation of the sharpener removed from its housing, with a part in section.

Figure 4 is a longitudinal sectional view taken through the sharpener with parts in section and in elevation and illustrates the sharpener in operative position.

Figure 5 is an end elevation looking into the open end of the housing.

Figure 6 is a sectional view taken approximately on line 6-6 of Figure 4, looking in the direction of the arrows.

Figure 7 is a sectional view taken approximately on line 7-7 of Figure 4, looking in the direction of the arrows.

Figure 8 is a view of the rack member which constitutes a part of the sharpener.

Figure 9 is a similar view of the spring member.

Referring to the drawings in detail, it will be noted that I have illustrated a mechanical pencil constructed to accommodate my sharpener, but I want it understood that the sharpener can be constructed as a unit separate and distinct from a pencil and can be used with any type of mechanical pencil, or pencils and the like of any kind as well as the usual wood cased lead pencil now in general use.

The body of the pencil is indicated by the reference numeral 1 and has one end portion tapered in the usual manner to provide the writing end or the end through which projects the lead refill, as clearly shown in Figure 1. The opposite end portion of the pencil is reduced to frictionally receive the housing 2 of my sharpener, and this reduced portion provides an annular shoulder for the open end of the housing which is tubular. The housing not only accommodates the sharpener parts, but also encloses the eraser of the pencil when the sharpener is not in use as will be noted upon inspection of Figure 2, and the housing may have secured thereto a clip as shown in Figure 1.

The outer end of the housing 2 is reduced as at 3 and secured to the reduced end is a rack member 4 which is provided with a bore extending longitudinally therethrough and includes a ring 5 having extending therefrom rack teeth 6 for a purpose which will be presently apparent. The ring 5 together with the rack teeth are arranged within the reduced end, and passing through the bore of the rack member is a shaft 7 that has secured to its outer end a knob 8 through the instrumentality of a pin 9 as shown in Figure 4. The knob is serrated to provide a finger gripping surface, and the shaft has formed with its inner end a disk 10 from which extends strips 11, one of the ends of which are secured within the disk 10, while their opposite ends are secured within a block 12.

The block 12 is substantially disk shape

but has provided in its sides recesses forming bearings for one of the ends of a pair of shafts 13, and the opposite ends of these shafts are journaled in bearing bores arranged in the disk 10. The shafts 13 are disposed at right angles with respect to the strips 11 and have secured thereto adjacent one end sprocket gears 14 that are arranged in mesh with the teeth 6 of the rack member

10 4 as clearly shown in Figure 7, while secured to the shafts 13 adjacent the opposite ends thereof are sharpening rollers 15 which are truncated conical shape and are arranged to cooperate with each other for sharpening 15 the lead refill of the pencil as clearly shown in Figure 4.

In order to hold the ends of the shafts 13 in the recesses of the block 12, I provide a spring member 16 that is substantially U- 20 shape in formation and has its bight portion secured in slots arranged in the strips 11, the strips being enlarged as at 17 to provide the slots as will be noted upon inspection of Figure 4 and the spring member is secured 25 in the slots by a cross piece 18 that has its ends secured to the strips as shown in Figure 3. The arms of the spring member 16 are disposed at an inclination with respect to each other and in diverging relation as 30 shown in Figure 9, and the free portions of the arms which are indicated by the reference numeral 19 are bent at right angles with respect to the remaining portions thereof to be arranged in parallelism with the recesses 35 of the block 12, the free portions are cut away to provide a bearing surface for cooperation with the recesses of the block 12 to accommodate the shafts 13 as clearly shown in Figure 6.

40 The block 12 has formed therethrough a bore to receive the outer end of the tapered portion of the body of the pencil as shown in Figure 4, and the bore of the block is restricted for the passage of the lead refill 45 therethrough, with the result the portion of the bore which accommodates the end of the tapered portion acts in the capacity as a stop for said end, but the housing is of a size whereby it fits the tapered portion of the 50 pencil adjacent its juncture with the remaining portion of the body. Frictionally secured within the housing is a relatively thick disk block 20 that has one of its faces recessed to accommodate the projecting portion of the 55 block 12, and the disk block 20 is provided with a bore that registers with the bore of the block 12 as will be noted upon inspection of Figure 4. The opposite face of the disk block is tapered to a slight degree for directing 60 the lead toward the bore thereof.

The tapered faces of the sharpening rollers are of course provided with teeth, and when it is desired to use the sharpener in the form as shown, it is removed from the eraser end 65 of the pencil to the writing end thereof or

from the position as shown in Figure 2, to the position as shown in Figure 4. The knob 8 is rotated which results in the rotation of the sharpening rollers 15 and this action is accomplished through the medium of the shafts 70 13 and the sprocket gears 14, with the result the lead will be sharpened in order to provide an efficient writing point as will be apparent.

The spring arms urge the rollers toward 75 each other and provide cushion means therefore, with the result breakage of the lead during the sharpening action is prevented, yet at the same time the lead is sharpened in an expeditious manner.

80 It is thought from the foregoing description that the advantages and novel features of my invention will be readily apparent.

I desire it to be understood that I may 85 make changes in the construction and in the combination and arrangement of the several parts, provided that such changes fall within the scope of the appended claim.

What I claim is:

A pencil sharpener that can be carried by a 90 pencil and comprising a housing, a pair of shafts arranged in said housing, a disk rotatably receiving one of the ends of said shafts, a rack member secured to one end of said housing and provided with a bore, means 95 passing through said bore and secured to said disk, a knob secured to the last mentioned means for rotating said disk to rotate the shafts about the axis of the disk, sprocket gears secured to said shafts and meshing with 100 the teeth of the rack member to rotate each of the shafts about its axis, a block having recesses arranged therein to receive the opposite ends of said shafts, strips secured to the block and disk respectively, a spring member 105 secured to said strips and including arms having free ends formed to cooperate with the recesses to provide bearings for the said opposite ends of the shafts, sharpening rollers secured to said shafts and disposed for cooperation, and means for directing lead to the sharpening rollers.

110 In testimony whereof I affix my signature.
WILLIAM H. WHITFORD.
